(57) **CLAIM**

The ornamental design for an outdoor toy set for children as shown and described.

DESCRIPTION

FIG. 1 is a front, right, and top perspective view of a toy base of an outdoor toy set for children shown separately for ease of illustration, according to my new design;

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right, and top perspective view of a toy accessory for the outdoor toy set for children shown separately for ease of illustration, according to my new design;

FIG. 10 is a rear, left and bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof.

FIG. 16 is a bottom plan view thereof.

FIG. 17 is a front, right, and top perspective view of the toy base and the toy accessory of the outdoor toy set for children shown in a combination state.

FIG. 18 is a front, right and top perspective view of the toy accessories 2 of the outdoor toy set for children shown separately for ease of illustration;

FIG. 19 is a rear, left and bottom perspective view thereof.

FIG. 20 is a front elevation view thereof.

FIG. 21 is a rear elevation view thereof.

FIG. 22 is a left side elevation view thereof.

FIG. 23 is a right side elevation view thereof.

FIG. 24 is a top plan view thereof.

FIG. 25 is a bottom plan view thereof.

FIG. 26 is another front, right and top perspective view of the toy base and toy accessories 2 in a combination state.

FIG. 27 is a front, right and top perspective view of the toy accessories 3 of the outdoor toy set for children shown separately for ease of illustration;

FIG. 28 is a rear, left and bottom perspective view thereof.

FIG. 29 is a front elevation view thereof.

FIG. 30 is a rear elevation view thereof.

FIG. 31 is a left side elevation view thereof.

FIG. 32 is a right side elevation view thereof.

FIG. 33 is a top plan view thereof.

FIG. 34 is a bottom plan view thereof.

FIG. 35 is another front, right and top perspective view of the toy base and toy accessories 3 in a combination state.

(Continued)

FIG. 36 is a front, right and top perspective view of the toy accessories 4 of the outdoor toy set for children shown separately for ease of illustration;

FIG. 37 is a rear, left and bottom perspective view thereof.

FIG. 38 is a front elevation view thereof.

FIG. 39 is a rear elevation view thereof.

FIG. 40 is a left side elevation view thereof.

FIG. 41 is a right side elevation view thereof.

FIG. 42 is a top plan view thereof.

FIG. 43 is a bottom plan view thereof; and,

FIG. 44 is another front, right and top perspective view of the toy base and toy accessories 4 in a combination state. The dashed broken lines depict portions of the outdoor toy set for children that form no part of the claimed design.
